FORK LIFT TYPE INDUSTRIAL PLATFORM PALLET OR THE LIKE

Charles G. Cardwell, Bartlesville, Okla., and Morris E. Speck, Akron, Ohio, assignors to Phillips Petroleum Company, Bartlesville, Okla.

Filed Sept. 9, 1974, Ser. No. 504,068

Term of patent 14 years

Int. Cl. D9—90

U.S. Cl. D12—53

FIG. 1

FIG. 2

FIG. 3

FIG. 4

FIG. 5

FIG. 6

FIG. 7

FIG. 1 is a top plan view of a fork lift type industrial platform pallet or the like showing our new design;

FIG. 2 is a side elevational view thereof, the opposite side being the same as the side shown herein;

FIG. 3 is the front elevational view thereof, the rear being the same as the front shown herein;

FIG. 4 is an elevational view in cross section taken along line 4-4 in FIG. 1;

FIG. 5 is an elevational view in cross section taken along line 5-5 in FIG. 1;

FIG. 6 is an elevational view in cross section taken along line 6-6 in FIG. 1; and

FIG. 7 is an elevational view in cross section taken along line 7-7 in FIG. 1.

We claim:

The ornamental design for a fork lift type industrial platform pallet or the like, as shown.
